Primary Examiner — Michael C Stout*Assistant Examiner* — Fitzgerald L Butac(74) *Attorney, Agent, or Firm* — Dale F. Regelman;
Grossman, Tucker, Perreault & Pfleger, PLLC(57) **CLAIM**

The ornamental design for a fluid drilling head, as shown and described.

DESCRIPTION

FIG. 1 is a perspective view of a fluid drilling head;
FIG. 2 is top view thereof;
FIG. 3 is bottom view thereof;
FIG. 4 is a first side view thereof;
FIG. 5 is a second side view thereof;
FIG. 6 is a front view thereof; and,
FIG. 7 is a rear view thereof.
